UNITED STATES PATENT OFFICE.

FREDERICK G. YAWMAN, OF ROCHESTER, NEW YORK.

WORK-HOLDER FOR COPY-HOLDERS.

1,261,888.

Specification of Letters Patent.

Patented Apr. 9, 1918.

Original application filed April 17, 1916, Serial No. 91,584. Divided and this application filed July 2, 1917. Serial No. 178,187.

To all whom it may concern:

Be it known that I, FREDERICK G. YAWMAN, a citizen of the United States, and resident of Rochester, in the county of Monroe and State of New York, have invented 5 certain new and useful Improvements in Work-Holders for Copy-Holders, of which the following is a specification.

The present invention relates to work 10 holders for copy-holders of the type in which the work holder secures the work in a pendant condition, and an object of the invention is to provide a construction in which the weight of the pendant work tends 15 to cause the work clamping means to more firmly hold the work on the work holder. Another object of the invention is to provide a novel means of securing the work clamping means on the work holder.

20 To these and other ends, the invention consists of certain parts and combinations of parts, all of which will be hereinafter described, the novel features being pointed out in the appended claims.

25 In the drawings:—

Figure 1 is a front view of the upper portion of a work holder embodying the present invention;

Fig. 2 is a side view of such upper portion;

Fig. 3 is a vertical section of the upper portion, Fig. 1; and

Fig. 4 is an enlarged fragmentary view of the rear face of the work holder in proximity to the upper end of such holder.

The present application is a division of an application filed by me on April 17, 1916, Serial No. 91,584. In the construction illustrated in said application a work holder is 40 movable on a frame to carry the work past a stationary line guide, as is common in a number of different machines in this art. While the present invention is illustrated in connection with a machine of the type 45 disclosed in my hereinbefore mentioned application, it is apparent that it is not limited to this type of copy holder, but is designed for use in any construction in which the work is held in a pendant condition.

50 Referring more particularly to the drawings, 1 indicates the work holding member in the form of a sheet metal plate which has its opposite edges rolled at 2, and guided upon rods 3 on the supporting frame 4. The 55 upper edge of this plate 1 is rolled at 5,

and is arranged in spaced relation to the upper ends of the guide rolls or tubes 2. Within the roll 5 and resting upon the upper ends of the tubes 2 is a clamp-supporting member 6 preferably formed from a sheet 60 metal strip with its longitudinal edges rolled, one of such rolls being received within the roll 5, and the other resting upon the upper ends of the tube 2. At opposite ends of the clamp-supporting member 6 two forwardly- 65 and downwardly-projecting arms 7 are provided to act to support the work-clamping member.

The clamping-member in this instance consists of a bar 8 having laterally-extending arms 9 at opposite ends connected with portions 10 which turn in the arms 7 below the bar portion 8. A finger piece portion 11 may be provided on the clamp member beyond the portions 10 to facilitate the turning of the clamp member on its pivot portions 10. Coil springs 11^a may be connected to the bar 8 near opposite ends of the latter, said springs being preferably anchored to lugs 12 on the arms 7 below the pivot portions 10. These springs tend to hold the bar portion 8 toward the plate 1, and if the bar portion 8 be swung on its pivots 10 outwardly away from the plate 1, until the lugs or stops 13 are engaged by the arms 9, then 85 the springs 11 will act to hold the clamping bar 8 away from the work holder plate 1. If desired, the clamping bar 8 may be provided at intervals with rubber or other friction sleeves 14.

90 For holding turned leaves, a coil spring 15 may be provided, said spring having its ends connected to upwardly-extending lugs 16 on the plate 7, so that the spring lies horizontally above the upper end of the work-supporting plate 1, and may be flexed laterally to permit the introduction of the leaves beneath it and the upper edge of the plate.

To secure the work to the work holder, the finger pieces 11 are manipulated to throw 100 the clamping bar outwardly away from the plate 1. The work is then placed against the plate with its upper edge in proximity to the upper edge of the plate, after which the finger pieces 11 are again manipulated 105 to throw the bar 8 toward the work. Owing to the fact that the turning axis of the clamping bar 8 is below the bar, the latter tends to swing toward the plate or work holding member 1 under the weight of the 110

work held by the bar, thus causing the clamp bar 8 to create a binding action on the work proportional to the weight of the work, and preventing the work from being released due to the action of its weight. As the clamp bar 8 is carried by a frame 6, which is connected to the work supporting plate in the manner shown, it is possible to increase or decrease the length of the clamp-
5 ing member by removing the latter and its supporting plate 6 from the plate 1, and fitting another clamp and supporting member to said plate of a different length. This is a desirable feature in a device of this kind, for it has been that in different offices work of different lengths must be held in the copy holder, and the present arrangement permits the securing of a clamping member which will hold work of any width.
10
15
20 What I claim as my invention and desire to secure by Letters Patent is:—

1. A work holder comprising a work holding member formed from sheet metal with rolled guides at opposite sides and a 25 rolled edge spaced from the upper ends of the rolled guides, a clamp-supporting member engaging within the roll at the upper edge and resting upon the upper ends of the rolled guides, and a clamping device carried by said clamp-supporting member.
30

2. A work holder comprising a work holding member mounted to support the work in a pendant condition, supporting

arms projecting forwardly from opposite sides of the work holding member near the 35 upper end of the latter, and a pivotally mounted clamping bar supported by said arms, the pivots of said bar being below the clamping portion thereof so that the weight of the work tends to draw the bar 40 toward the work holding member.

3. A work holder comprising a work holding member mounted to support the work in a pendant condition, supporting arms projecting forwardly from opposite 45 sides of the work holding member near the upper end of the latter, a clamping member having a bar portion and laterally-extending arms at the ends of the bar portion, said ends being pivoted to the arms below the bar portion, and springs acting on said clamping member to hold it toward the work support or away from the work support.
50

4. A work holder comprising a work holding member mounted to support the 55 work in a pendant condition, and a pivotally mounted clamp for holding the work to the work holding member, the pivotal axis of said clamp being parallel with the plane of the work holding member in spaced 60 relation to the front of said member and below the work engaging portion of the clamp so that the weight of the work tends to draw the work engaging portion of the clamp toward the work holding member.

FREDERICK G. YAWMAN.
